DESIGN FOR A WEDDING VEIL

Adolf Frank, Long Beach, N. Y.

Application April 13, 1938, Serial No. 76,478

Term of patent 14 years

To whom it may concern:

Be it known that I, Adolf Frank, a citizen of the United States, residing in Long Beach, county of Nassau and State of New York, have invented a new, original, and ornamental Design for a Wedding Veil, of which the following is a specification, reference being had to the accompanying drawing, forming a part thereof, in which the single figure is a side perspective view of a wedding veil embodying my design and illustrating its appearance when worn.

The design comprises a fitted, hemi-spherical net cap portion with an embroidered border and having a net veil of substantial length stitched around the bottom border of the cap portion, said veil having a border matching that of the cap portion, as shown.

I claim:

The ornamental design for a wedding veil, substantially as shown and described.

ADOLF FRANK.
